UNITED STATES PATENT OFFICE.

SAMUEL RILEY LEWIS, OF RATON, TERRITORY OF NEW MEXICO.

FEEDER-LIFTER.

SPECIFICATION forming part of Letters Patent No. 486,486, dated November 22, 1892.

Application filed January 11, 1892. Serial No. 417,778. (No model.)

To all whom it may concern:

Be it known that I, SAMUEL RILEY LEWIS, a citizen of the United States, residing at Raton, in the county of Colfax and the Territory of New Mexico, have invented a new and useful Feeder-Lifter, of which the following is a specification.

My invention relates to improvements in the means for lifting the feeders of oil-cups on machinery; and the object of my improvement is to afford facilities for the extraction of the feeders from such oil-cups. I attain this object by the use of the instrument illustrated in the accompanying drawings.

15 In the drawings, Figure 1 is a view of the feeder-lifter applied to and shown in connection with an oil-cup and feeder. Fig. 2 is a transverse sectional view of the jaws of the lifter.

20 The device is preferably made of steel and comprises two pivotally-connected members A A', provided, respectively, with jaws B B and having handles or reins C C'. The jaws are interiorly chambered or concaved, as 25 shown in Fig. 2, whereby when closed an elliptical recess D is formed between the opposing

concave surfaces thereof. One of the handles C terminates in a ring c and the other C' terminates in a spiral coil or twist c', and the spiral spring E fits and engages the spiral 30 coil or twist c' and is provided with an arm E', which is notched at e to engage the handle C. The tendency of this spring, which is held in place by the spiral coil or twist, is to separate the jaws of the device.

35 F represents the oil-cup, and a the feeder which projects therefrom.

What I claim, and desire to secure by Letters Patent, is—

40 A device of the class described, having pivotally-connected members provided with concaved jaws and handles, one of the handles terminating in a ring and the other terminating in a spiral coil or twist c', and the actuating-spring having a spirally-coiled portion 45 which fits and engages the spiral coil or twist, and an arm which engages the opposite handle, substantially as specified.

SAMUEL RILEY LEWIS.
